ATTORNEYS

UNITED STATES PATENT OFFICE.

RAYMOND V. OWEN, OF ST. LOUIS, MISSOURI, ASSIGNOR TO THE EDWIN F. GUTH COMPANY, OF ST. LOUIS, MISSOURI, A CORPORATION OF MISSOURI.

HOUSING FOR LIGHTING-FIXTURE SUPPORTS.

Application filed July 15, 1925. Serial No. 43,707.

My invention relates to the art of illumination, and has for its purpose to provide a housing for wall brackets, principally, which will also provide anchoring means for an additional porcelain receptacle which will serve as an additional outlet, which outlet may be used for any desired purpose, such as the attachment of an electric iron, and the like.

A further object is to provide a housing 10 for lighting fixture supports, which will coordinate with the canopy to be used, so as to effectually conceal all of the securing parts.

My invention consists of certain details of construction in which

15 Fig. 1 is an elevation partly in vertical section to show the interior construction;

Fig. 2 is a disassembled view of the construction of my device.

Referring to the accompanying drawings, 20 reference numeral 10 is used to indicate a junction box of the usual type, provided with screw-threaded stud 11, to which is secured a metal strap 12, which is U shaped in con-

formation, the outer end being provided with 25 a screw-threaded orifice to receive a securing screw 13. The numeral 14 indicates a metal bridge with offset ends 15 and 16 respectively, in each of which is a screw-threaded orifice to receive the elongated-headed screws 17

30 and 18, respectively. The numeral 19 indicates an extension ring, designed to be seated over the junction box, the metal bridge overlapping the said ring so that when the bridge is firmly seated in position, it will securely

35 fasten the ring to the junction box. The extension ring, which is really a housing, has an extended portion 20, which is preferably located at the lower end, and has an orifice therein to receive the plug receptacle 21,

40 which plug is of the usual type and adapted to receive the contacting ends of a mating portion of a plug secured to an electrical appliance, such as an iron (not shown). The extension ring 19 has a circular shoulder

45 stamped thereon, which, by construction, is of the proper size as to permit the canopy to fit over it so that the canopy 22 will fit flush against the body portion of the extension ring. This is for the purpose of effectually

concealing the securing means for the extension ring, canopy, and the like, and to provide a fixture in which all of the usual securing means are concealed.

The canopy 22 is provided with two key-hole slots 23 and 24 designed to receive the 55 elongated screws 17 and 18, by means of which the canopy is seated upon the extension ring 19 and secured thereto.

A socket 25 is secured in the usual manner to the junction box 10 and concealed by the canopy 22, and the glass shade 26 is provided with a flaring lip 27 which overlies the heads of the elongated screws when the shade is fitted against the canopy. A securing ring 28 engages the inside of the shade 26 and screws on to the lamp socket, thus providing means for effectually securing the shade to the canopy.

The operation of the elements of my device is obvious.

Having thus described my invention what I claim and desire to secure by Letters Patent of the United States is:

1. A housing for an outlet box having a circular portion, there being an opening 75 therein, a shoulder surrounding said opening, a downwardly extending portion formed integral therewith, said extension being adapted to receive an electric plug receptacle, a canopy which fits said shoulder, a strap secured to the junction box, a pair of elongated screws mounted therein, there being keyhole slots in said canopy adapted to receive said screw heads.

2. A housing for an outlet box having a 85 circular portion, there being an opening therein, a shoulder surrounding said opening, a downwardly extending portion formed integral therewith, said extension being adapted to receive an electric plug receptacle, a canopy which fits said shoulder, a strap secured to the junction box, a pair of elongated screws mounted therein, there being keyhole slots in said canopy adapted to receive said screw heads, a shade and means to 90 attach said shade to said canopy and conceal said slot and screw heads.

RAYMOND V. OWEN.
